UNITED STATES PATENT OFFICE

100,576

DESIGN FOR A CARPET SWEEPER

Swift Miller, Wauwatosa, Wis., assignor to E. R.
Wagner Manufacturing Company, Milwaukee,
Wis., a corporation of Wisconsin

Application June 25, 1935, Serial No. 57,395

Term of patent 7 years

To all whom it may concern:

Be it known that I, Swift Miller, a citizen of the United States, residing at Wauwatosa, in the county of Milwaukee and State of Wisconsin, have invented a new, original, and ornamental Design for Carpet Sweepers, of which the following is a specification, reference being had to the accompanying drawing, forming a part thereof, and in which:

Figure 1 is a view in front elevation showing a carpet sweeper embodying my new design;

Figure 2 is a view thereof in top plan; and

Figure 3 is a view in end elevation.

The handle is shown in the fragmentary condition for convenience of illustration.

The dominant feature of my design resides in

combining a casing and end plates and in forming the end plates so that all major angles and corners are eliminated, the surfaces of the end plates lying in different planes and being curved longitudinally and transversely so that said surfaces blend easily and smoothly into each other and with the contour of the casing and slope continuously from the center of the sweeper toward the front and rear and the casing having its outer surface conforming to the fore and aft contour of the end plates, the entire sweeper giving a pleasing and streamline effect.

I claim:

The ornamental design for a carpet sweeper as shown and described.

SWIFT MILLER.
